UNITED STATES PATENT OFFICE.

ALBERT BROADMEYER, OF HARRISBURG, PENNSYLVANIA, ASSIGNOR TO THE W. O. HICKOK MANUFACTURING COMPANY, OF HARRISBURG, PENNSYLVANIA, A CORPORATION OF PENNSYLVANIA.

FEEDING MECHANISM FOR RULING MACHINES AND THE LIKE.

Application filed April 8, 1926. Serial No. 100,699.

The present invention relates particularly to means for effecting and controlling the movement of sheets in ruling apparatus and the like.

5 One of the principal objects is to provide novel means of a simple and effective character, whereby two sheet moving means or devices can have different timed relations, while operating at predetermined speeds. 10 Another and important object is to provide novel means whereby one instrument, as for example, the first feeder of a duplex machine, can be thrown out of operation, while the remaining mechanism continues, in order 15 that the sheets already in the apparatus will pass through the same.

In the accompanying drawings:—

Figure 1 is a diagrammatic plan view of the lay-out of an L ruling machine, showing 20 the location and general arrangement of the novel mechanism.

Figure 2 is a detail side elevation on an enlarged scale, looking in the direction of the arrow A of Figure 1,

25 Figure 3 is a detail cross sectional view taken on the line 3—3 of Figure 2,

Figure 4 is a sectional view on the line 4—4 of Figure 3,

30 Figure 5 is a sectional view on the line 5—5 of Figure 3,

Figure 6 is an inner face view of the head on the driven shaft section,

Figure 7 is a similar view of the head on the driving shaft section.

35 Figure 8 is a detail longitudinal sectional view through the connection between the driving shaft section and the cam sleeve,

Figures 9 and 10 are inner face views of the two connecting heads of the driving 40 shaft section and cam sleeve,

Figure 11 is a sectional view on the line 11—11 of Figure 5,

Figure 12 is a sectional view on the line 12—12 of Figure 11,

45 Figure 13 is a cross sectional view taken on the line 13—13 of Figure 1, and on an enlarged scale,

Figure 14 is a plan view of the structure shown in Figure 13.

50 Figure 15 is a longitudinal sectional view through one of the suction rollers,

Figure 16 is a sectional view on the line 16—16 of Figure 15,

Figure 17 is a detail sectional view of the controlling valve for the first feed roller.

55 The invention is disclosed in the form of an L ruling machine, in which sheets are first moved under ruling pens in one direction, and are then caused to move in a right angular direction beneath a second set of 60 ruling pens to rule lines thereon at right angles to the first lines. The lay-out of such a machine is disclosed in Figure 1, wherein a feeder is shown diagrammatically at 17. This delivers sheets to the first ruling machine 18, and from the ruling machine 18, the sheets are delivered to a turner or direction-changing device, indicated at 19. From this apparatus 19 they are fed to a second ruling machine 20. Inasmuch as the 65 feeder 17 and ruling machines 18 and 20 may be of well-known character, it is believed to be unnecessary to show and describe them in detail, as their make-up is well-known to those skilled in the art.

70 The feeder 17 preferably employs a rotary suction feeding roller 21, such as that disclosed in my prior Patent, No. 1,494,303, dated May 13, 1924. An embodiment of the same is illustrated in Figures 15 and 16, 75 whereon a driven shaft 22 has adjustably mounted thereon the roller 21. This roller is provided with rows of peripheral suction ports 23 in communication with bores 24 that in turn communicate with suction passageways 25, the bores and passageways opening through one end of the roller. The roller is journaled in a head 26, having a suction port 27, with which the inner ends of the passageways 25 successively align. The port 27 is in communication with a suction pipe 28 leading to a suitable suction or exhaust pump 29, driven by any suitable means. In this pipe 28, and preferably at the sheet turning mechanism 19, is located a controlling 80 valve casing 30. As shown in Figure 17, this valve casing contains a plunger valve 31, having a reduced portion 32 that is movable to a position to allow communication between the pump 29 and the suction roller 21, 85 and is movable to a different position to cut off communication between the said pump 29 and roller 21 and open a vent 33 to the pump. 90 The sheets, after passing the ruling machine 18, are carried by endless tapes 34 into 95 the sheet turning mechanism 19, and are fed 100 through the valve casing 30. The sheet turning mechanism 19, and are fed 105

therefrom to the second ruling machine 20 by a suction roller 35. This suction roller is preferably of the same construction as the suction roller 21 above described. The suction roller 35 has an exhaust conduit 36 leading to a valve casing 37, and from said valve casing a conduit 38 leads to a suction or exhaust pump 39.

Extending across the path of the sheets 10 carried by the tapes 34, is a stop bar 40, and as shown in Figures 13 and 14, secured by brackets 41 to this bar, is a suction pipe 42, having depending nozzles 43 with open lower ends, these nozzles overlying the tapes 15 34 in advance of the stop bar. The nozzles preferably have forwardly extending guide fingers 44 with upturned free terminals 45 that direct the sheets carried by the tapes 34 beneath the nozzles and against the stop 20 bar 40. Referring now to Figure 4, the valve casing 37 contains a plunger valve 46 having a reduced portion 47 that is movable into and out of position to afford communication between the suction conduit sections 36 and 38 and thus connect the feed roller 35 to the pump 39. The valve 46 also has a free end provided with a passageway 48 that opens through its lower end, and has a lateral port 49 that is movable into communication with the conduit 38 leading to the pump 39 when the reduced portion 47 moves upwardly to cut off communication between the conduit section 36 and 38. This 25 lower end of the valve is connected by a pipe 50 with the suction pipe 42.

Journaled on the rear end of the machine is a main drive shaft section 51, operated by any suitable means, and having fixed thereto between its ends a collar or head 52. 30 Another head 53 is fixed to the inner end of the shaft section 51. Slidably and rotatably mounted on the drive shaft section 51, between the heads 52 and 53, is a sleeve 54, one end of which may be knurled, as shown 35 at 55, forming a handpiece, so that it may be readily moved. The other end of the sleeve carries a cam 56, and this cam is provided with a pin 57, adapted to engage in any of a series of sockets 58 formed in the head or collar 52. The cam is normally held 40 locked to the collar by means of a coiled spring 59 interposed between the knurled end of the sleeve 54 and the head 53 fixed to the shaft section 51. Riding on the cam 45 56, as illustrated in Figure 4, is the bearing member 60 of a rocker arm 61, and this rocker arm has a link connection 62 with the valve 46. Obviously, therefore, upon each rotation of the driving shaft section 51, the valve 31 is moved to opened, and then to closed position.

Alined with the inner end of the driving shaft section 51 is a driven shaft section 63, which as shown in Figure 11, has fixed to it 55 a head 64 provided with a peripheral groove

65. The head 53 of the driving shaft section 51 has a longitudinally disposed driving pin 66 adapted to engage a driven pin 67 slidably mounted in the head 64 and extending across the groove 65. This pin is normally held 70 in its projected position or in the path of the pin 66 by a leaf spring 68. The pin 67 is provided with a notch 69, one face of which is inclined, as shown at 70 in Figure 12. A rock shaft 71, located alongside the 75 shaft sections 51 and 63 (see Fig. 3) is provided with a crank arm 72 carrying a cross head 73 at its free end, and this head has a tapered shoe 74 adapted to enter the groove 69 of the pin 67, as shown in Figure 12, so as to be engaged by the inclined face 70 of the pin. Consequently the rotation of the head will cause the pin to be withdrawn out of the path of the driving pin 66, thus disconnecting the shaft 63 from the shaft 80 51. The head 73, when in a position to have the shoe 74 engage the pin 67, is also in the path of pins 75 projecting from the periphery of the head 64, and these pins therefore will abut against the head 73 and positively 85 stop the rotation of the driven shaft section 63.

This driven shaft section carries a cam 76, on which rides the bearing element 77 of a rocker arm 78, and this arm has a link 95 connection 79 with the valve 31 that controls communication between the pump 29 and the feeder suction roller 21.

The rocker arm 78, as shown more particularly in Figure 2, also serves to operate a sheet counter, for example a register illustrated at 80, and the operating shaft 81 thereof has a crank arm connection 82 with the rocker arm 78. The driven shaft section 83 furthermore is preferably provided 100 with an eccentric 83 operating a pitman 84, and this pitman actuates a swinging pawl 85 operating on a ratchet wheel 86. The ratchet wheel carries a sprocket wheel 87, having an endless sprocket chain 88, and this sprocket chain is provided with one or more lugs 89 adapted to swing an arm 90, and for example, operate a circuit closer 91 of the alarm or other device. The operation of all these instrumentalities is obviously controlled by the clutch actuating shoe 74 that moves the driven pin 67 out of engagement with the driving pin 66 or permits it to have such engagement.

The operation of the apparatus is as follows. Assuming that all the parts are in operation, it will be evident that suction is periodically created in the suction roller 21, and thus in a manner readily understood, said suction roller will deliver sheets successively to the first ruling machine 18. Passing from this ruling machine, these sheets will be successively carried by the tapes 34 against the stop bar 40, and inasmuch as suction is periodically created in 130

the second roller 35, this roller will start the sheets at right angles from their first direction of movement and send them to the second ruling machine 20.

5 Inasmuch as the controlling valves for the first suction roller 21 and second suction roller 35 are actuated by the common driving shaft 51, each of the cams that operate the valves will be given one movement upon 10 each rotation of the shaft. Their timed relations, however, can be altered. Thus, by sliding the sleeve 54, the pin 57 of the cam 56 can be disengaged from one of the sockets 58, and engaged in another socket. Thus 15 the cam can be fixed in different positions about the shaft. On the other hand the cam 76, which operates the valve 31 controlling the first machine, will always be in one fixed position with respect to the driving shaft 51, 20 since there is but one driving pin 66, and one driven pin 67. The two cams therefore, though operating at the same speed, can have their relative positions altered, and the timing of the operation of the two suction 25 rolls correspondingly altered. If, however, it is desired to stop the initial feed of the apparatus, it is only necessary to cause the crank arm 72 to swing downwardly, so that the shoe 74 will enter the annular groove 65, 30 whereupon as the parts continue to operate, the pin 69 will be withdrawn from the path of the pin 66, and the driven shaft 63 stopped. This obviously stops the operation 35 of the valve 31, and the arrangement is such that the valve is stopped in its closed position, with the pump 29 out of communication with the suction roller 21. The initial feed is consequently stopped, but the remainder of the apparatus continues in operation, so that the sheets already fed from 40 the machine, continue on through. It will also be noted that when the driven shaft section 63 is stopped, the counting or registering mechanism is also stopped, so that 45 there is no danger of the erroneous counting of sheets when the initial feed of sheets is stopped.

From the foregoing, it is thought that the construction, operation and many advantages of the herein described invention 50 will be apparent to those skilled in the art, without further description, and it will be understood that various changes in the size, shape, proportion and minor details of construction may be resorted to without departing from the spirit or sacrificing any of the advantages of the invention.

What I claim is:

1. In apparatus of the character set forth, 60 the combination with two instrumentalities for successively operating on sheets, of a drive shaft, cams driven by the shaft for periodically operating said instrumentalities, and means for connecting and disconnecting

the cam that operates the first instrumentality. 65

2. In apparatus of the character set forth, the combination with two instrumentalities for successively operating on sheets, of a drive shaft, cams for periodically operating 70 said instrumentalities, one being driven by the shaft, a clutch between the other cam and the shaft, and means for operating the clutch to cause the latter to be connected to and disconnected from the shaft. 75

3. In apparatus of the character set forth, the combination with two instrumentalities for successively operating on sheets, of a drive shaft, cams for periodically operating 80 said instrumentalities, means for adjustably connecting one of the cams at different positions to the shaft, a clutch between the other cam and the shaft for connecting it thereto in a fixed relation to the shaft, and means for operating the clutch. 85

4. In apparatus of the character set forth, the combination with mechanisms for operating on sheets, of feeding means for delivering the sheets successively to the mechanisms, operating means for the feeding means including a shaft, and actuating devices for the respective feeding means driven thereby, and means for connecting and disconnecting the actuating device of the first 90 feeder while permitting that of the second 95 feeder to continue in operation.

5. In apparatus of the character set forth, the combination with mechanisms for operating on sheets, of feeding means for delivering the sheets successively to the mechanisms, operating means for the feeding means including a shaft, an actuating device for one feeder rotatable with respect to the shaft and having means for fixing it thereto in different positions about the shaft, a second actuating device for the second feeder, and means for connecting and disconnecting the actuating device of the first 100 feeder while permitting that of the second 105 feeder to continue in operation. 110

6. In apparatus of the character set forth, the combination with mechanisms for operating on sheets, of feeding means for delivering the sheets successively to the mechanisms, operating means for the feeding means including a shaft, a sleeve rotatably mounted on the shaft, an actuating device carried by the sleeve, means for fixing the sleeve and device to the shaft in different positions about the latter, a second actuating device for the other feeder, and a clutch for connecting the second device to and disconnecting it from the shaft. 115

7. In apparatus of the character set forth, the combination with mechanisms for operating on sheets, of feeding means for delivering the sheets successively to the mechanisms, operating means for the feeding 120 means

means including a shaft, a sleeve rotatably mounted on the shaft, an actuating device carried by the sleeve, means for fixing the sleeve and device to the shaft in different relations about the latter, a second actuating device for the other feeder, and a clutch for connecting the second device to the shaft in a fixed predetermined relation and disconnecting it from the shaft to permit the latter and the first device to operate independently of the second.

8. In apparatus of the character set forth, the combination with mechanism for operating successively on sheets, of a feeder for delivering sheets successively to the mechanism, sheet counting means, a common operating element for the feeder and the counting mechanism, and means for stopping the feeder and counting means to stop the feed of sheets to the mechanism while permitting the latter to continue operation on the sheets already fed and counted.

9. In apparatus of the character set forth, the combination with mechanism for operating successively on sheets, of a feeder for delivering sheets successively to the mechanism, sheet counting means, a drive shaft, means for operating the feeder and counting means including a cam, and means for clutching the cam to and unclutching it from the shaft to stop the feeder and counting mechanism in order to stop the feed of the sheets to the mechanism while permitting the latter to continue operation on the sheets already fed and counted.

10. In apparatus of the character set forth, the combination with two mechanisms for operating on sheets, of a feeder for delivering sheets to the first mechanism, a second feeder for transferring sheets from the first mechanism to the second mechanism, a counting mechanism operating with the first feeder, and means for stopping the operation of the first feeder and counting mechanism, while permitting the second feeder to operate and transfer to the second mechanism the sheets already counted and fed to the first mechanism.

11. In apparatus of the character set forth, the combination with two mechanisms for successively operating on sheets, of a feeder for delivering sheets successively to the first mechanism, a feeder for transferring sheets from the first mechanism to the second mechanism, a common driver for both feeders, an actuating device for each feeder driven by the driver, and means for clutching and unclutching the driver and driving element of the first feeder, while permitting the second to continue operation to transfer to the second device the sheets already fed to the first device by the first feeder.

12. In apparatus of the character set forth, the combination with two mechanisms for successively operating on sheets, of a suction

roller for delivering sheets successively to the first mechanism, a second suction roller for transferring sheets from the first mechanism to the second mechanism, a suction controlling valve for each suction roller, operating means for the respective valves, including an actuating device for each, and means for stopping one of the actuating devices while permitting the other to continue in operation.

13. In apparatus of the character set forth, the combination with two mechanisms for successively operating on sheets, of a suction roller for delivering sheets successively to the first mechanism, a second suction roller for transferring sheets from the first mechanism to the second mechanism, a suction controlling valve for each suction roller, operating means for the respective valves, including an actuating device for each, and means for stopping the actuating device of the controlling valve for the first suction roller while permitting the actuating device for the transfer roller to continue in operation.

14. In apparatus of the character set forth, the combination with two mechanisms for successively operating on sheets, of a first suction roller for feeding sheets to the first mechanism, a second suction roller for transferring sheets from the first to the second mechanism, a suction controlling valve for each roller, a drive shaft, cams for operating the valves driven by the shaft, and means for fixing the cams to the shaft in different relative positions about the same to change the relation of operation of the valves.

15. In apparatus of the character set forth, the combination with two mechanisms for successively operating on sheets, of a first suction roller for feeding sheets to the first mechanism, a second suction roller for transferring sheets from the first to the second mechanism, a suction controlling valve for each roller, a drive shaft, cams for operating the valves driven by the shaft, one of said cams being slidably and rotatably mounted on the shaft, and interlocking devices carried by the cam and shaft for fixing the latter in different positions thereto and around the same and in different relations to the other cam to change the relation of the operation of the valves.

16. In apparatus of the character set forth, the combination with two mechanisms for successively operating on sheets, of a first suction roller for feeding sheets to the first mechanism, a second suction roller for transferring sheets from the first to the second mechanism, a suction controlling valve for each roller, a drive shaft, cams for operating the valves driven by the shaft, and a clutch for connecting and disconnecting one of the cams and the shaft.

17. In apparatus of the character set forth,

the combination with two mechanisms for successively operating on sheets, of a first suction roller for feeding sheets to the first mechanism, a second suction roller for transferring sheets from the first to the second mechanism, a suction controlling valve for each roller, a drive shaft, cams for operating the valves driven by the shaft, and a clutch for connecting and disconnecting the cam that operates the controlling valve for the first suction roller.

18. In apparatus of the character set forth, the combination with two mechanisms for successively operating on sheets, of a first suction roller for feeding sheets to the first mechanism, a second suction roller for transferring sheets from the first to the second mechanism, a suction controlling valve for each roller, a drive shaft, cams for operating the valves driven by the shaft, a clutch for connecting and disconnecting the cam that operates the controlling valve for the first suction roller, and means for securing the cam for the valve of the second suction roller at different places about the shaft to vary the relation of operations of the two valves.

19. In apparatus of the character set forth, the combination with two mechanisms for successively operating on sheets, of a first suction roller for feeding sheets to the first mechanism, a second suction roller for transferring sheets from the first to the second mechanism, a suction controlling valve for each roller, a driving shaft having a head, a sleeve rotatable and slidable on the driving shaft and having a cam for actuating the valve of the second suction roller, said sleeve and head having interlocking means for holding the sleeve, and cam fixed to the shaft in different positions about the same, a cam for actuating the valve of the first suction roller, and means for detachably clutching the second cam to the shaft always in the same relation thereto.

20. In apparatus of the character set forth, the combination with a driving shaft, of an actuating cam slidably and rotatably mounted on the driving shaft, said shaft and cam having means that detachably interlock to hold the cam on the shaft in different adjusted relations about the same, and means for maintaining the means in interlocked relation.

21. In apparatus of the character set forth, the combination with a driving shaft, of a sleeve slidably and rotatably mounted on the driving shaft and having a cam fixed thereto, said shaft having a head and said sleeve and cam having means that detachably interlock with the head to hold the cam on the shaft in different adjusted relations about the same, and a spring on the shaft bearing against the sleeve and maintaining the means in interlocked relation.

22. In apparatus of the character set forth, the combination with a rotatable driving member, of a rotatable driven member, an actuating cam carried by the driven member, abutting elements carried by the two members for transmitting motion from one to the other, one of said elements being movable on its member into and out of the path of the other, and means movable into and out of the path of the movable element to cause its retraction from the path of the other element.

23. In apparatus of the character set forth, the combination with a rotatable driving member, of a rotatable driven member, an actuating cam carried by the driven member, abutting elements carried by the two members for transmitting motion from one to the other, one of said elements being movable on its member into and out of the path of the other, and a shoe movable into and out of the path of the movable element to cause its retraction from the path of the other element.

24. In apparatus of the character set forth, the combination with a rotatable driving member, of a rotatable driven member, an actuating cam carried by the driven member, abutting elements carried by the two members for transmitting motion from one to the other, one of said elements being movable on its member into and out of the path of the other, a shoe movable into and out of the path of the movable element to cause its retraction from the path of the other element, and a stop carried by the driven member and movable into engagement with the shoe to stop the driven member when the elements are disengaged.

25. In apparatus of the character set forth, the combination with a driving shaft, of a driven shaft alined therewith, an actuating cam on the driven shaft, an abutment on one shaft, an abutment slidably mounted on the other shaft and movable into and out of the path of the first abutment to cause the driven shaft to be driven by the driving shaft or be freed therefrom, a swinging arm having a shoe movable into the path of the sliding abutment to slide the same out of the path of the first abutment, and a stop on the driven shaft that engages the shoe to stop the driven shaft and cam when said shoe is engaged with the sliding abutment.

26. In apparatus of the character set forth, the combination with a ruling machine, of a suction roller for delivering sheets thereto, a second ruling machine, a suction roller for transferring sheets from the first to the second ruling machine, a suction controlling valve for each suction roller, and means for operating the valves in predetermined timed relation.

27. In apparatus of the character set forth, the combination with a ruling ma-

- chine, of a suction roller for delivering sheets thereto, a second ruling machine, a suction roller for transferring sheets from the first to the second ruling machine, a suction controlling valve for each suction roller, and means for operating the valves at a fixed speed relation and in various timed relations.
28. In apparatus of the character set forth, the combination with a ruling machine, of a suction roller for delivering sheets thereto, a second ruling machine, a suction roller for transferring sheets from the first to the second ruling machine, a suction controlling valve for each suction roller, and means for operating the valves, means for moving the cams at the same speed, and means for changing the timed relation of the cams.
29. In apparatus of the character set forth, the combination with a ruling machine, of a suction roller for delivering sheets thereto, a second ruling machine, a suction roller for transferring sheets from the first to the second ruling machine, a suction controlling valve for each suction roller, a driving shaft, valve-operating cams connected to the shaft and operating at the same speed, and means for relatively adjusting the cams on the shaft to vary the relation of the operation of the valves.
30. In apparatus of the character set forth, the combination with a ruling machine, of a suction roller for delivering sheets thereto, a second ruling machine, a suction roller for transferring sheets from the first to the second ruling machine, a suction controlling valve for each suction roller, a driving shaft, valve-operating cams operated by the shaft, and means for connecting and disconnecting the shaft, and one of the cams while the other is continued in operation.
31. In apparatus of the character set forth, the combination with a ruling machine, of a suction roller for delivering sheets thereto, a second ruling machine, a suction roller for transferring sheets from the first to the second ruling machine, a suction controlling valve for each suction roller, a driving shaft, valve-operating cams operated by the shaft, and means for connecting and disconnecting the shaft and the cam that operates the controlling valve of the first suction roller.
32. In apparatus of the character set forth, the combination with a ruling machine, of a suction roller for delivering sheets thereto, a second ruling machine, a suction roller for transferring sheets from the first to the second ruling machine, a suction controlling valve for each suction roller, a driving shaft, a cam rotatably mounted on the shaft and operating the valve of the second suction roller, means for fixing the cam to the shaft at different positions about the same, a cam for operating the first suction roller, and clutch means for detachably connecting the second cam to the driving shaft in a predetermined fixed relation.
33. In apparatus of the character set forth, the combination with a ruling machine, of a suction roller for delivering sheets thereto, a second ruling machine, a suction roller for transferring sheets from the first to the second ruling machine, a suction controlling valve for each suction roller, a driving shaft, a cam slidably and rotatably mounted on the shaft and operating the valve of the second suction roller, detachable interfitting means on the shaft and cam for fixing the cam to the shaft at different positions about the same, a driven shaft, a cam on the driven shaft for operating the first suction roller, clutch means for connecting and disconnecting the driving and driven shafts, and means for stopping the driven shaft when the driving shaft is at a standstill.

In testimony whereof, I affix my signature.

ALBERT BROADMEYER.
